(57) **CLAIM**

The ornamental design for a wall/ceiling panel, as shown and described.

DESCRIPTION

FIG. 1 is a front perspective view of a wall/ceiling panel; FIG. 2 is a rear perspective view of the wall/ceiling panel of FIG. 1;

FIG. 3 is a front view of the wall/ceiling panel of FIG. 1; FIG. 4 is a rear view of the wall/ceiling panel of FIG. 1; FIG. 5 is a top view of the wall/ceiling panel of FIG. 1; FIG. 6 is a bottom view of the wall/ceiling panel of FIG. 1; FIG. 7 is a left side view of the wall/ceiling panel of FIG. 1; FIG. 8 is a right side view of the wall/ceiling panel of FIG. 1;

FIG. 9 is an enlarged view of the portion of the wall/ceiling panel of FIG. 7 identified by window 9 in FIG. 7; and, FIG. 10 is an enlarged view of the portion of the wall/ceiling panel of FIG. 7 identified by window 10 in FIG. 7.

The drawings contain a symbolic break. The portion between the break lines form no part of the claimed design. The dash-dash broken lines in the figures depict portions of the wall/ceiling panel that form no part of the claimed design. The dash-dot-dash broken lines represent boundaries of the enlarged views and form not part of the claimed design.

1 Claim, 10 Drawing Sheets
